UNITED STATES PATENT OFFICE.

JAMES G. BLUNT, OF SCHENECTADY, NEW YORK.

LOCOMOTIVE DRAWBAR.

Application filed February 9, 1924. Serial No. 691,674.

To all whom it may concern:

Be it known that I, JAMES G. BLUNT, a citizen of the United States, and a resident of Schenectady, in the county of Schenectady and State of New York, have invented a certain new and useful Improvement in Locomotive Drawbars, of which improvement the following is a specification.

My invention relates to appliances for detachably connecting locomotive engines and their tenders, and is of the general class or type of that set forth in Letters Patent of the United States No. 1,293,315, granted and issued to me under date of February 4, 1919.

10 The object of my present invention is to provide an appliance of such type which shall be suitably and desirably applicable in connection with locomotives in which space limitations prevent the application of the pin type of drawbars heretofore ordinarily applied.

The improvement claimed is hereinafter fully set forth.

The increase in the number of locomotives of present standard construction, which are equipped with "boosters," or mechanical stokers, or both, renders it necessary to provide means for coupling the engine and tender, which shall be exempt from the extreme difficulty, and sometimes impossibility, of applying and removing draw bars of the present types, by reason of the location of the accessories above mentioned, immediately above and below the usual location of the draw bar pin. Reduction of the space occupied vertically by the draw bar appliance, therefore becomes essential, and my invention is designed to so accomplish it as to avoid the objection above noted, without impairing the strength of the connection or involving substantial increased structural or operative cost.

In the accompanying drawings, Figure 1 is a side view, in elevation, of the adjoining portions of a locomotive and tender, illustrating an application of my invention; Fig. 2, a plan view, partly in section, and on an enlarged scale, of an appliance embodying my invention; and, Fig. 3, a vertical longitudinal central section through the same.

In the practice of my invention, referring descriptively to the specific embodiment thereof which is herein exemplified, the locomotive, A, is herein shown as equipped with a mechanical stoker, a, by which fuel is transferred from the tender, B, to the

firebox of the locomotive. It is also shown as equipped with a "booster," or auxiliary traction engine, C, which is mounted on the trailing truck, D. The respective location 60 of the stoker and the booster, and the fact that sufficient clearance must be provided, above the booster, in order that it may oscillate with its support, in passing over uneven track, and sufficient clearance be also 65 provided for the insertion, in a vertical direction, of the draw bar pin, if of the ordinary type, will indicate the difficulty, before stated, of applying such type.

The draw bar appliance of my invention, 70 for the detachable connection of the locomotive and tender, which is herein set forth, is of substantially the following construction. The two members, 1 and 1^a, of the duplex draw bar, extending normally parallel with the longitudinal central plane of the locomotive, have heads on their forward ends, and are coupled to a draw bar pocket, 3, fixed to the rear of the frame of the locomotive, by a substantially horizontal connecting member, in the form of a draw bar pin, 2, which passes through eyes, 1^b, in the heads of the draw bars, and is preferably, as shown, of substantially rectangular section. The draw bar pin is insertible from 80 either side of the locomotive, and extends entirely through, and bears on, the draw bar pocket, 3. The top and bottom faces of the eyes, 1^b, of the draw bars, are inclined in opposite directions, so as to make the 85 eyes of greater depth at their front than their rear ends, in order to accommodate the rise and fall of the tender, relatively to the locomotive, in passing over uneven track, and their front and rear ends are convexly 90 curved, as shown in Fig. 2, to admit of the angular horizontal movement of the draw bars, when the locomotive is passing a curve 95 of the track. Lugs, 3^a, are formed on the side walls of the draw bar pocket, to provide increased bearing surface for the draw 100 bar pin, 2. The draw bar pin is held in position by bolts, 3^b, passing through the lugs, 3^a, and having nuts, 3^c, engaging threads on their ends.

The rear ends of the draw bars, 1 and 1^a, are coupled, by pins, 4, 4^a, insertible from below, to a cylindrical pivot block, 6, fitted freely in, and bearing peripherally on, the draw bar pocket, 5, of the tender. The 110 coupling pins, 4, 4^a, are held in position by a stop pin, 4^b, passing through a stop plate

5^a, which is secured to the bottom of the draw bar pocket, 5, which holds the pivot block, 6, vertically in position.

I claim as my invention and desire to 5 secure by Letters Patent:

1. In a railroad draft gear, the combination with two vehicles, of duplicate draw bars, pivotally connected on vertical axes to one of said vehicles; a draw bar pocket, 10 fixed on the other vehicle; a substantially horizontal connecting pin, fitting in said pocket and coupling the draw bars thereto; and removable means for securing the connecting pin in operative position.
- 15 2. In a railroad draft gear, the combination with two vehicles, of a pivot block, fitted to move about its axis on one of said vehicles; a duplex draw bar; the two sec-

tions of which are pivotally connected to the pivot block; and a substantially horizontal connecting member, coupling the draw bar sections to the other vehicle.

3. In a railroad draft gear, the combination with two vehicles, of a pivot block rotatably mounted on one of said vehicles, duplex draw bars pivotally secured at one end in said block on vertical axes, a draw bar pocket carried by the other vehicle, and a substantially rectangular connecting pin carried by said pocket and passing through the other ends of said draw bars, the eyes in said ends being of tapered section to accommodate relative vertical movements of the vehicles.

JAMES G. BLUNT.
